(57) **CLAIM**

The ornamental design for an ultrasound probe and removable cap in combination, as shown and described.

DESCRIPTION

FIG. 1 FIG. 1 is a top, right perspective view of an ultrasound probe and removable cap in combination showing our new design;

FIG. 2 is a front view thereof;

FIG. 3 is a back view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a top, right perspective view thereof in an exploded configuration; and,

FIG. 9 is a top, left perspective view thereof.

The broken lines in the drawings represent portions of the ultrasound probe that form no part of the claimed design.
